UNITED STATES PATENT OFFICE

136,397

DESIGN FOR A SEWING MACHINE

Malcolm S. Park, Mount Kisco, N. Y., assignor to
The Singer Manufacturing Company, Elizabeth,
N. J., a corporation of New Jersey

Application July 22, 1943, Serial No. 110,730

Term of patent 14 years

To all whom it may concern:

Be it known that I, Malcolm S. Park, a citizen of the United States, residing at Mount Kisco, in the county of Westchester and State of New York, have invented a new, original, and ornamental Design for a Sewing Machine, of which the following is a specification, reference being had to the accompanying drawing, forming a part thereof.

Fig. 1 is a front perspective view of a sewing machine showing my new design.

Fig. 2 is a rear perspective view of the sewing machine shown in Fig. 1.

I claim:

The ornamental design for a sewing machine, as shown.

MALCOLM S. PARK.
